UNITED STATES PATENT OFFICE.

ALFRED COTTON, OF NEWARK, NEW JERSEY.

BRICK FOR FURNACE CONSTRUCTION.

No. 907,683.

Specification of Letters Patent.

Patented Dec. 22, 1908.

Original application filed March 26, 1906, Serial No. 307,982. Divided and this application filed July 1, 1908.
Serial No. 441,495.

To all whom it may concern:

Be it known that I, ALFRED COTTON, a subject of the King of Great Britain, and residing in Newark, State of New Jersey, have invented 5 certain new and useful Improvements in Bricks for Furnace Construction, of which the following is a specification, reference being had thereto in the accompanying drawings, in which—

Figure 1 is a side elevation of the inner 10 face of a fire box wall showing my improved brick in position; Fig. 2 a transverse sectional view thereof on the line II—II of Fig. 1; Fig. 3 a horizontal sectional view thereof on the line III—III of Fig. 2; Fig. 4 a perspective 15 view of the brick; Fig. 5 a bottom plan view thereof; and Fig. 6 a transverse vertical sectional view on the line VI—VI of Fig. 4.

In constructing smoke-consuming steam 20 boiler furnaces it is customary in some forms of construction, to form flues in the fire box walls and to place these flues in communication with the fire box by openings through said walls. As ordinarily constructed the openings from the flues to the 25 fire box are frequently choked with molten slag and cinders. The openings through the walls are usually formed by transverse channels in the bricks, and these channels so weaken the bricks that they are frequently 30 broken during conveyance to the place of erection and during the operation of building them into the furnace wall. Openings formed in this manner usually discharge an 35 unbroken jet of comparatively cold air, or air and steam, which does not mingle or combine readily with the combustible gases and whose effect is therefore local.

It is the main object of this invention to 40 provide a fire brick for use in building fire box walls, so designed that the openings from the flues to the fire box will communicate with triangular pockets in the fire box wall, one wall of said pocket being horizontal and the said openings being formed at an 45 angle to said horizontal wall, whereby the inflowing jets from the flues will strike said horizontal walls and be diverted thereby. By this construction the openings from the 50 flues to the fire box will terminate within the fire box wall and will be protected by said wall from molten slag and cinders. It is, of course, to be understood that while the brick is especially designed for use in furnace wall construction it may be adapted for 55 other uses.

Referring to the various parts by numerals, 1 designates the fire box wall; 2 the usual flue formed therein for supplying steam and air to the fire box above the grate; and 3 the brick by means of which the openings 60 from the flue to the fire box are formed. These bricks are of peculiar shape and are shown in detail in Figs. 4, 5 and 6. They are double the height and thickness of the ordinary fire brick and are undercut at each 65 end to form the inclined faces 4. The upper edges of these faces terminate on inclined lines 5 which meet at a point 6 midway between the ends of the brick at the lower edge thereof. The upper ends of the lines 5 intersect the ends of the brick at a point slightly 70 below the upper surface of the brick, as shown clearly in Fig. 1. The face 7 of the brick is vertical, except, of course, where it is undercut to form the inclined faces 4; and 75 the outer face, that is, that face which is not exposed to the fire, is downwardly and outwardly inclined, as at 8, as shown clearly in Fig. 2, except the narrow vertical portion 9 at the lower edge of the brick. In each end 80 of the brick is formed a groove 10 which is at an angle to the horizontal lower surface of the brick and inclines from the rear side of the brick downwardly and inwardly toward the front or fire box face thereof. When 85 these bricks are arranged end to end the grooves in the adjoining ends of two bricks form downwardly and inwardly inclined cylindrical passages through which air and steam may pass from the flues into the fire 90 box. These passages open into the annular 95 cavities 11 formed by the undercut portions of adjoining bricks and the course of common or standard brick below the undercut bricks; and the inflowing jets of air 100 and steam are directed against the bottoms of these cavities formed, in the arrangement shown, by the standard bricks, and are thereby heated and deflected into the fire box in a thin divergent (or fan-shaped) 105 sheet. The air being very effectively spread, will be thoroughly mixed with the combustible gases; and being heated, will promote active combustion. The bricks are substantially rectangular in transverse section 110 at a point midway between their ends and are approximately right angle triangles at their ends, as shown in Fig. 4. The two undercut faces are oblique to the vertical plane of the brick and are also oblique to the hori- 115

zontal plane of the brick. When these bricks are arranged end to end in the fire wall, between ordinary horizontal courses of common or standard bricks, they form cavities having triangular horizontal bottoms and in free communication with the fire box through triangular openings, the apex of the opening being directly over the middle of the forward or fire box edge of the triangular bottom and the upper or inclined sides, of the cavity being formed by the undercut oblique faces of two adjoining bricks. It will be observed that the brick may be inverted in some cases so that the horizontal face will be the top of the triangular cavity. The air-jets will then be directed upwardly instead of downwardly as above described; but without altering the general principle. It will be noted that in building a fire wall of my peculiar form of brick the outlet ends of the passages formed by the grooves 10 are within the fire box wall, and that they open into the angular recesses formed in said wall. The bottom of these recesses are 25 horizontal. The brick is not easily broken as its cross sectional area is greatest at the middle of its length. It will be readily understood that a brick of this peculiar construction may be used in ventilating walls, 30 and for various other purposes.

This application is a division of my application filed March 26th, 1906, Serial No. 307,982, for steam boiler furnaces.

Having thus described my invention, what 35 I claim as new and desire to secure by Letters Patent, is:—

1. A brick for wall construction having one longitudinal vertical face, portions of said longitudinal face being cut away at opposite ends of said longitudinal vertical face and on the same edge thereof to form inclined faces, and the brick being provided at each of its ends with a groove, whereby when two bricks are arranged end to end the 45 cut away portions form a cavity and the grooves form a passage opening into said cavity.

2. A brick for wall construction formed

with a vertical flat face, two horizontal faces, and two inclined faces, said inclined faces meeting at the middle of one longitudinal edge of the vertical flat face and being oblique to the vertical and horizontal planes of the brick and at an angle to each other and extending from the ends of the brick to the middle thereof, the brick being provided at each of its ends with a passage, whereby when two bricks are arranged end to end the adjoining inclined faces of the bricks will form a triangular cavity, and the passages in the ends of the bricks will open into said cavity.

3. A brick for wall construction formed with a vertical flat face, two horizontal faces, and two inclined faces, said inclined faces meeting at the middle of one longitudinal edge of the vertical flat face and being oblique to the vertical and horizontal planes of the brick and at an angle to each other, and extending from the ends of the brick to the 70 middle thereof, each brick being provided at each of its ends with an inclined groove, whereby when two bricks are arranged end to end the adjoining inclined faces of the bricks will form a triangular cavity and the 75 grooves will form passages through the brick and opening into said cavity.

4. A brick for wall construction having one longitudinal vertical face, portions of said longitudinal face being cut away at opposite ends of said longitudinal vertical face and on the same longitudinal edge thereof to form inclined faces, and the brick being provided at each of its ends with a passage, whereby when two bricks are arranged end 80 to end the cut away portions form a cavity and the passage at the end of the brick opens into said cavity.

In testimony whereof I hereunto affix my signature in the presence of two witnesses 90 this 24th day of June 1908.

ALFRED COTTON.
